CLAIM

The ornamental design for golf club head, as shown and described.

DESCRIPTION

FIG. 1 is a perspective bottom view of my new design for a golf club head;

FIG. 2 is a top plan view thereof;

FIG. 3 is a front elevation view thereof;

FIG. 4 is a toe end view thereof;

FIG. 5 is a heel end view thereof;

FIG. 6 is a bottom plan view thereof; and,

FIG. 7 is a rear elevational view thereof.

The broken lines shown on the drawings form no part of the claimed design.
